US00D543524S

(12) **United States Design Patent** (10) **Patent No.:** **US D543,524 S**
Shin et al. (45) **Date of Patent:** **** May 29, 2007**

(54) **PORTABLE PHONE**

(75) Inventors: **Seo-Young Shin**, Seoul (KR); **Nam-Mi Kim**, Seoul (KR); **Chang-Hwan Hwang**, Goyang-Si (KR)

(73) Assignee: **Samsung Electronics Co., Ltd.**, Suwon-Si (KR)

(**) Term: **14 Years**

(21) Appl. No.: **29/234,729**(22) Filed: **Jul. 22, 2005**(30) **Foreign Application Priority Data**

Jan. 26, 2005 (KR) 30-2005-0002627

(51) **LOC (8) Cl.** ..... **14-03**(52) **U.S. Cl.** **D14/138**

(58) **Field of Classification Search** D14/191, D14/138, 147-148, 247-248, 144, 496, 156, D14/341-347; 379/433.01-433.13; 455/575.3, 455/566, 575.1, 556.1, 556.2, 90.3; D21/517; D16/208

Primary Examiner—Jeffrey Asch(74) *Attorney, Agent, or Firm*—Staas & Halsey LLP(57) **CLAIM**

The ornamental design for the portable phone, as shown and described.

DESCRIPTION

FIG. 1 is a perspective view of the portable phone showing our design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an open view thereof.
